[57]

ABSTRACT

A banding apparatus for flexible bands or tape and comprising a clip having a passage therethrough to receive portions of lashing tape extending around an article to be lashed or banded and a tape dispensing and tightening device operative to effect movement of clip portions to engage a plurality of teeth on the clip into engagement with the tape portions to hold said tape or band portions against movement. The tape dispensing device has a tape compartment and means for mounting a roll of flexible lashing tape therein and a passage extending through the tape compartment and ratchet means mounted on the tape compartment for effecting retractive movement of a portion of the tape through the passage and into the tape compartment thereby moving the clip into engagement with the article to be lashed and setting the teeth in the tape portions.

BANDING APPARATUS

The present invention relates to lashing systems and more particularly to a lashing system using flexible bands of suitable material, for example, a plastic or nylon tape, and having a clip movable into engagement with an article to be lashed in response to tightening movement of a portion of a lashing tape as effected by a tape tightening device thereby setting teeth on the clip into portions of the lashing tape extending therethrough.

Heretofore, it has been common in lashing operations to extend a plurality of metal wires or bands around articles to be lashed together with metal clips laterally deformed to grip and join overlapping end portions of the banding members. It has been found that a flat tape of a suitable plastic, such as nylon, effects lashing and eliminates many difficulties experienced with metal wire or tape. The plastic tape has a substantial area of contact with the articles to be lashed thereby distributing the lashing force as there is no tendency to indent or cut the articles to be lashed. The plastic tape is substantially inert, long wearing, and does not abrade the articles to be lashed in the event of relative movement therebetween, such as may occur during handling. While various fittings have been used to anchor or handle the wire lashing and metal straps, such devices are not suitable for use in applying and holding plastic tape. Also the plastic tape is flexible, substantially nonextensible, and tends to return or straighten unless bent double, therefore, it has been difficult to secure and maintain in anchored condition.

The principal objects of the present invention are: to provide a tape or band tightening and anchoring system usable with flexible band or tape for lashing articles together, such as for banding packages, securing articles to pallets, and the like; to provide such a tape lashing system having a clip operative to firmly engage adjacent portions of such flexible tape to prevent relative movement between the adjacent portions thereof when tightened around articles to be lashed; to provide such a tape lashing system including a tape dispensing device selectively operative to retract a portion of the lashing tape; to provide such a device and a clip on the tape whereby retracting the tape moves the clip into engagement with the article to be lashed and further retraction tightens the tape and effects anchoring engagement of the clip into the tape; to provide such a tape lashing system having a tape dispenser with tightening mechanism operative to effect tension in the lashing tape and a clip operative to anchor portions of the lashing tape together thereby maintaining said portions in tension; and to provide such a tape tightening system which has a tape dispensing and tightening device and tape holding clips which are economical to manufacture, easily and efficiently operated for lashing articles, and particularly well adapted for the proposed use.

Other objects and advantages of this invention will become apparent from the following description taken in connection with the accompanying drawings wherein are set forth by way of illustration and example certain embodiments of this invention.

FIG. 1 is a perspective view of a tape dispensing and tightening device embodying features of the present invention.

FIG. 2 is a sectional view through the tape dispensing and tightening device taken on the line through 2—2, FIG. 3.

FIG. 3 is a sectional view through the tape dispensing and tightening device taken on a line 3—3, FIG. 2.

FIG. 4 is a transverse sectional view through the tape dispensing and tightening device taken on the line 4—4, FIG. 2.

FIG. 5 is a perspective view of a clip blank with tape engaging members cut therein.

FIG. 6 is an enlarged sectional view through the tape holding clip in formed position.

FIG. 7 is a partial view of an article and dispensing device and clip in position for tightening of the tape.

FIG. 8 is a partial view of an article with the tape anchored by a clip.

Referring more in detail to the drawings:

The reference numeral 1 generally designates a tape dispensing and tightening device operative to move a portion of a flexible lashing tape or band 2 to effect engagement between a holding clip 3 and an article or articles 4 to be lashed thereby effecting locking engagement of portions 5 on the clip 3 with portions of the lashing tape 2 extending therethrough. A suitable tape is a substantially flat tape of nylon or the like of suitable width. It is found that for many banding operations a tape width in the nature of one-fourth inch is suitable, however, wider tape maybe used for heavy duty banding.

The tape holding clip 3 is formed or relatively hard bendable metal and preferably is made from a blank 6, which, while in planar form, is stamped to provide cuts 7 of an irregular shape to form tape engaging members 8. As illustrated in FIG. 5, the members 8 are in the form of teeth in opposed meshing rows. The cuts 7 are such that the total length of the opening 9 formed between the teeth extends transversely of the clip for a width greater than the width of the tape 2 with the ends 10 of the opening spaced from the sides 11 of the clip. It has been found that a hard bendable metal member about three-eighths inch wide, one-fourth inch long, and 0.025 inch thick, is suitable for the blank for one-fourth inch width tape. The opening 9 in such a blank is preferably approximately nine thirty-seconds inch wide and equally spaced from the wide edges of the blank. The blank 6 is then bent whereby the bend extends through the rows of teeth with the mid-portions 12 curved, as at 13, and end portions of the clip form legs 14 extending from the curved portion 13 in a generally U-shaped form. When bent to this position, the teeth or members 8 remain substantially in a line with the respective leg portion 14 so that the ends of the teeth are spaced apart, as at 15, providing an elongate opening through which the tape 2 may be moved. The tape extends from a dispenser 1 through the opening 9 between the legs 14 and then around an article or articles 4 to be lashed, then back between the legs 14 and through the opening 9, the clip being such that when the tape is tightened the legs 14 of the clip are drawn against the article 16 being lashed to spread said legs apart and move the teeth 8 together to engage the tape portions extending therebetween to provide a positive grip between the clip and the tape, as later described.

The tape dispenser 1 has a housing 18 in which is located a compartment 19 for receiving a roll 20 of the lashing tape 2. The housing has a side wall 21 and a peripheral wall 22 defining an open-sided compartment 19, which open side is closed by a cover 23, as later described. A ratchet wheel 24 is rotatably mounted in the housing adjacent the side wall 21 with a tape spool 25 extending therefrom toward the open side of the compartment. The housing 18 has a handle member 26 extending therefrom with an upstanding ear 27, and the cover 23 has bifurcated ears 28 cooperating with said ear 27 and with a pivot pin 29 extending through said ears to pivotally mount the cover for movement toward and away from the open end of the compartment. When in closed position, the cover 23 engages edges 30 of the peripheral wall 22. The cover is secured in compartment closing position by a suitable latch 31, and in the illustrated structure, the latch consists of a resilient latch member that engages over the housing remote from the pivot ears.

The housing 18 has elongate extension 32 extending therefrom in spaced relation to the handle 26, said extension 32 having a slot or passage 34 extending longitudinally therethrough and communicating with the compartment 19, as at 35, forming an inlet to the slot that is the dispensing opening for the tape. At the entrance opening, as at 36, rounded wear members 37 of hard material are inserted in recesses and serve as contact points for the tape being dispensed, the roll of tape being arranged whereby the tape is fed from adjacent the handle 26 and the slot is positioned relative thereto whereby there is a minimum of bend in the tape as it is fed from the roll. Feeding of the tape from the roll is resisted by a pawl 38 pivotally mounted by a pin 39 on ears 40

located on the wall 22. The pawl 38 has a portion extending through a slot 41 and terminating in a detent 42 for engaging with shoulders 48 formed by ratchet teeth 44. A spring 45 urges the pawl detent 42 into engagement with the ratchet so that tape can be dispensed only by depressing a portion 46 remote from the detent of the pawl to swing the pawl detent out of engagement with the ratchet.

The peripheral wall 22 has an opening 47 between the extension 32 and the handle 26. A ratchet lever 48 is pivotally mounted on the axle of the ratchet mounting and extends through the opening 47 in normally spaced relation from the handle 26. The ratchet lever 48 is urged away from the handle by a spring 49, the movement thereof being limited by engagement of the lever with the end of the opening 47 adjacent the extension 32. The lever is provided with a detent 50 pivotally mounted thereon and resiliently urged into engagement with the ratchet teeth whereby movement of the lever 48 toward the handle 26 effects rotation of the ratchet and the foll of tape tending to draw the tape back into the compartment.

The slot 34 opens from the same side as the compartment and said opening is normally closed by a cover plate 51 which has slots 52 receiving pins 53 mounted on the extension and having enlarged ends or members 54 to hold the plate in position. The slots 52 permit movement of the plate transversely of the slot or passage 34 to open same. Springs 55 urge the plate 51 to closed position, the movement being limited by the pins 53 engaging the ends of the slots, as at 56.

A tape cutting device 58 is mounted on the extension 32, said tape cutting device including a blade 59 mounted on an arm 60 pivotally connected to the extension 32, said blade and arm being movable across the slot or passage 34 at the end 61 of the extension to cut the tape flush with said end. After cutting of the tape, the end of the tape of the roll is moved outwardly of the slot 34 by a feeding means 62 in the form of a slide member 63 arranged on the lower portion of the extension 32 and having a resilient feed member 64 engaging the tape whereby movement of the slide member 63 toward the end of the extension 32 will tend to move the tape out of the dispensing slot or passage 34 when the pawl detent 42 is disengaged from the ratchet teeth 44.

In use, the pawl detent 42 is moved out of engagement with the teeth 44 on the ratchet wheel 24 and the lashing tape 2 is then moved outwardly from the tape compartment 14 through the slot or passage 34 by operating the slide member 63. After the end of the tape is exposed it is grasped and pulled while the detent 42 is disengaged from the ratchet teeth to dispense the desired amount of tape. The lashing tape 2 is extended through the opening 9 in a tape holding clip 3 and around the article 4 to be lashed. The free end of the lashing tape 2 is then moved through the opening 9 in the clip 3 then moved into the passage 34. The portion adjacent the free end of the tape 2 engages the teeth of the adjacent leg and also the end of the dispenser extension 32 is held at the teeth portion of the clip to aid in holding the free end of the tape to the clip as the other end is retracted. The clip 3 is positioned adjacent a flat or arcuate surface of the article 4 and the tape dispensing and tightening device 1 is operated to retract the lashing tape 2 in the passage 34 and tighten said tape around the article 4. This retracting movement is by operation of the ratchet lever 48 and the detent 50 thereon. The retractive movement of the lashing tape 2 forces the free ends of the legs 12 of the clip 3 into engagement with the article 4 thereby tending to separate the legs 12 which movement moves the teeth or portions 8 into engagement with the adjacent portions of the lashing tape 2 extending through the clip 3. When the lashing tape 2 is sufficiently tightened around the article 4 to be lashed and the teeth 8 firmly engage the portions of the lashing tape 2, the blade 59 is operated to cut the lashing tape 2 adjacent the free end 61 of the extension 32.

When it is desired to lash the next article, the slide member 63 is operated in combination with depressing the push portion 46 of the pawl 38 thereby feeding the lashing tape 2 outwardly through the passage 34. The pawl 38 is maintained out

of engagement with the ratchet wheel 24 until a sufficient portion of the lashing tape 2 has been moved out of the tape compartment 19.

It is to be understood that while I have illustrated and described one form of my invention it is not to be limited to the specific forms or arrangement of parts herein described and shown.

What I claim and desire to secure by Letters Patent is:

1. A banding system for articles, in combination
  - a. an elongate plastic tape that is a substantially flat strip of flexible nylon and substantially nonextensible,
  - b. a clip having a central transverse bend and spaced legs forming a generally U-shape with a transverse opening at said bend defined by opposed teeth members with said plastic tape adapted to extend through said opening and around an article having side surfaces and then back through said clip opening, with said clip legs and article side surface pressing tape portions therebetween, said opposed teeth members intermeshing in response to spreading of said legs,
  - c. said clip legs being adapted to spread in response to tensioning the tape around the article and through the clip opening to engage the clip teeth with the tape to bite same and maintain the tension thereof around the article.
2. A banding system as set forth in claim 1 and including,
  - a. a tape dispensing structure having a roll of tape from which the flat tape extends through the clip opening and around articles and back through the clip opening,
  - b. means in said tape dispensing structure operative to retract the tape and tension the tape around the article until anchored by said clip,
  - c. means operative to sever the tape between the clip and tape dispensing structure.
3. A tape dispensing and tightening device for banding articles comprising:
  - a. a housing having tape compartment therein,
  - b. means within said tape compartment for mounting a roll of flexible lashing tape therein,
  - c. a passage extending from the housing for movement of tape therethrough,
  - d. means operative to release the tape roll whereby tape is extendable from the housing passage,
  - e. means mounted on said housing and operative to effect retractive movement of tape through said passage and into the tape compartment,
  - f. means movably mounted on said housing and extending into said passage for engaging tape therein and operative to feed tape outwardly through said passage.
4. The tape dispensing and tightening device as set forth in claim 3 wherein said tape is dispensed and extended around articles for banding and including:
  - a. fastener means for engaging the tape adjacent articles around which the tape extends and holding the tension of the tape, said fastener comprising a clip having folded portions defining spaced legs,
  - b. said clip having a passage therethrough for the lashing tape to extend therethrough, and
  - c. a plurality of teeth on adjacent ends of said spaced legs adapted to intermesh and to engage the lashing tape when the free ends of the spaced legs are forced apart by engagement with an article to be lashed in response to retractive movement of a portion of the tape.
5. The tape dispensing and tightening device as set forth in claim 3 including:
  - a. means mounted on the housing adjacent an end of said passage and operative for cutting the tape.
6. The tape dispensing and tightening device as set forth in claim 3 including:
  - a. a passage cover movably mounted on said housing at one side of said passage, and
  - b. resilient means engaging said passage cover for urging same into a position over the side of the passage thereby closing same to prevent tape from moving laterally from said passage.

7. The tape dispensing and tightening device as set forth in claim 3 including:

- a. a handle on said housing and extending generally radially from the tape compartment,
- b. a cover for said tape compartment, said compartment cover being pivotally mounted adjacent said handle for swinging movement to open said tape compartment, said compartment cover having means thereon for engaging said housing remote from said handle to hold said cover in a closed position over said tape compartment.
- 8. A tape dispensing and tightening system for banding articles comprising:
- a. a housing having tape compartment defined by a side wall and a peripheral flange extending therefrom,
- b. means within said tape compartment for mounting a roll of flexible lashing tape therein,
- c. an extension on said housing and having a passage extending through same from the tape compartment for movement of tape therethrough,
- d. ratchet means mounted on said tape compartment for effecting retractive movement of tape through said passage and into the tape compartment,
- e. means movably mounted on said housing extension and having a portion extending into said passage in engagement with the tape for feeding tape outwardly therethrough,
- f. means mounted on said housing extension adjacent an end of said passage for cutting the tape after the desired amount of retractive movement,
- g. a passage cover movably mounted on said housing extension,
- h. resilient means engaging said passage cover for urging same into a position closing the passage through said extension,
- i. a handle extending generally radially from said tape compartment,
- j. a cover for said tape compartment, said compartment cover being pivotally mounted on said handle, said compartment cover having means thereon for engaging said housing remote from the handle to hold said cover in a closed position,

5

- k. a clip having folded portions defining spaced legs,
- l. a passage through said clip for the lashing tape to extend therethrough, and
- m. a plurality of teeth on adjacent ends of said spaced legs to engage the tape when the free ends of the spaced legs are forced apart by engagement with an article to be lashed in response to retractive movement of a portion of the tape.
- 9. A tape dispensing and tightening device for banding articles comprising:
- a. a housing having tape compartment therein,
- b. means within said tape compartment for mounting a roll of flexible lashing tape therein,
- c. a passage extending from the housing for movement of tape therethrough,
- d. means operative to release the tape roll whereby tape is extendable from the housing passage,
- e. means mounted on said housing and operative to effect retractive movement of tape through said passage and into the tape compartment,
- f. a handle on said housing and extending generally radially from the tape compartment,
- g. a cover for said tape compartment, said compartment cover being pivotally mounted adjacent said handle for swinging movement to open said tape compartment, said compartment cover having means thereon for engaging said housing remote from said handle to hold said cover in a closed position over said tape compartment,
- h. said housing having a side wall and peripheral flange defining the tape compartment,
- i. said means operative to retract the tape including a ratchet wheel rotatably mounted on said side wall of said tape compartment and a reciprocating lever and pawl for moving the ratchet wheel,
- j. said means releasing the tape roll including a second pawl pivoted on the housing and engagable with the ratchet wheel to prevent tape dispensing rotation thereof,
- k. the roll of flexible lashing tape being mounted on the ratchet wheel and movable therewith, and
- l. resilient means engaging said reciprocating lever to urge said lever and pawl therein away from the handle.
